US0D1025266S

(12) **United States Design Patent** (10) Patent No.: **US D1,025,266 S**
(45) Date of Patent: ** Apr. 30, 2024

(54) **FRAME FOR RACECAR SIMULATING DEVICE**

(71) Applicant: **Shanghai Coaslin Technology Co., Limited**, Shanghai (CN)

(72) Inventor: **Xiaofei Peng**, Shanghai (CN)

(73) Assignee: **SHANGHAI COASLIN TECHNOLOGY CO., LIMITED**, Shanghai (CN)

(**) Term: **15 Years**

(21) Appl. No.: **29/926,520**

(22) Filed: **Jan. 31, 2024**

(51) LOC (14) Cl. **21-01**

(52) U.S. Cl.

USPC **D21/733**

(58) **Field of Classification Search**
